(57) **CLAIM**

The ornamental design for a front combination lamp for automobile, as shown and described.

DESCRIPTION

FIG. 1 is a front and right perspective view of a front combination lamp for automobile, showing my new design. FIG. 2 is a front elevation view thereof.

FIG. 3 is a right side elevation view thereof.

FIG. 4 is a left side elevation view thereof.

FIG. 5 is a top plan view thereof; and,

FIG. 6 is a bottom plan view thereof.

The claimed design is indicated by the relatively dark portions, while the relatively and blurred portions form no part of the claimed design.

1 Claim, 6 Drawing Sheets
